UNITED STATES PATENT OFFICE.

JOSEPH A. WEST, OF SAN RAFAEL, CALIFORNIA.

VEHICLE-SEAT.

SPECIFICATION forming part of Letters Patent No. 396,250, dated January 15, 1889.

Application filed December 6, 1887. Renewed November 19, 1888. Serial No. 291,305. (No model.)

To all whom it may concern:

Be it known that I, JOSEPH A. WEST, a citizen of the United States, residing in San Rafael, in the county of Marin and State of California, have invented a new and useful Spring-Back for Buggy-Seats, of which the following is a specification.

My invention relates to improvements in a combined arm-rest and spring-back for buggies, which will be understood by reference to the accompanying drawings and the letters referring thereto.

Figure 1 is a side elevation of a buggy with my improvement attached. Fig. 2 is a side elevation, partly in section, showing my improvement attached to a broken part of a buggy-seat.

A represents a buggy-seat; B, the spring-back; C, the supporting-springs; D, the stationary coupling; E, the connecting-rod, which connects the arm-rest or seat-rail with the front of the seat; F, the sleeve by which the arm-rest or seat-rail is connected and adjusted; G, the seat-back spring, which gives elasticity to the seat-back; H, the adjusting coupling, which connects the arm-rest or seat-rail with the rod J for the purpose of connecting the spring-back.

I represents the pivot or joint by which the arm-rest or seat-rail is connected with the spring-back.

J represents the rod or part of the seat-rail which connects with the spring-back.

K represents the recess to cover the thread upon the inner part of the arm-rest or seat-rail.

L represents a stop on the end of the rod E, forming the bearing of the spring G.

The following is the construction of my improved combined arm-rest or seat-rail and spring-back.

I form the sleeve F and couplings D and H of brass or other metal capable of receiving

a neat finish. I cut a thread in the coupling H to receive the rod J, and I connect the 45 coupling D by forming a smooth hole for the rod E to pass through. The end of the rod E has a stop to receive the bearing of the spring G. I cut a thread on the rod J to operate in the coupling H, for the purpose of 50 adjusting the seat-rail, as will be shown. I form the spring-braces C of the best spring-steel.

The following is the operation of the invention.

The spring-braces C, forming the support of the back B, are firmly attached to the same and also to the seat A. The joint I allows the required play to adjust to the vibration of the back-supporting springs C, and as the 60 seat-back is pressed the springs yield, the spring G allowing the rod E to draw out in proportion to the weight or force applied. This arrangement allows an elastic and perfectly easy seat-back. When it is necessary 65 to tighten or stiffen up the spring-back, the sleeve F and connecting-couplings H and D are revolved. The coupling H, operating upon the thread of the rod J, lengthens or shortens the seat-rail, and consequently renders the 70 same more or less elastic, as required.

Having thus described my invention, what I claim, and desire to secure by Letters Patent, is—

In combined seat-rail and spring-braces for 75 buggies, the combined seat-rail and back, composed of the rods E and J, connected by the couplings H and D, the sleeve F, and spring G, in combination with the spring-back B and spring-supporting braces C, constructed and operated substantially as and 80 for the purposes set forth.

JOSEPH A. WEST.
